UNITED STATES PATENT OFFICE.

WILLIAM T. BAKER, OF FINDLAY, OHIO, ASSIGNOR OF TWO-THIRDS TO
RUSSELL MARVIN AND JOHN SHULL, BOTH OF SAME PLACE.

STEAM-ENGINE.

SPECIFICATION forming part of Letters Patent No. 280,710, dated July 3, 1883.

Application filed March 30, 1883. (No model.)

To all whom it may concern:

Be it known that I, WILLIAM T. BAKER, of Findlay, in the county of Hancock and State of Ohio, have invented certain new and useful 5 Improvements in Steam-Engines; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a front view of my improved steam-engine. Fig. 2 is a side view of the 15 same. Fig. 3 is a vertical sectional view on line $x-x$, Fig. 2. Fig. 4 is a similar view on line $y-y$, Figs. 1 and 3. Fig. 5 is a sectional detail view of one of the shaft-bearings. Figs. 20 6 and 7 are detail views of the piston-packing.

Similar letters of reference indicate corresponding parts in all the figures.

My invention has relation to rotary engines having an oscillating piston; and it consists in the detailed construction and combination of 25 parts of the same, as hereinafter more fully described and claimed.

In the accompanying drawings, the letter A indicates the cylinder, mounted upon a suitable base, and having an oscillating cylindrical 30 piston, B, provided with two diametrically-opposite wings, C, and mounted upon a shaft, D, having an oscillating crank, E, upon one end, which connects by a pitman or connecting-rod, F, with the wrist-pin G of a rotating crank or 35 disk, H, fastened upon the drive-shaft I. The inside of the cylinder has two sector-shaped recesses, J, diametrically opposite each other, preferably at the upper and lower side of the cylinder, and the two wings C of the piston 40 oscillate in these recesses.

K is the live-steam pipe, which enters the top of the cylinder and divides into two live-steam channels, L, passing down the sides of the cylinder, one upon each side, and opening 45 about half-way down on the same into the two cylindrical valve-chambers M, from each of which two steam-channels, N and O, open, leading to the upper and lower recesses of the cylinder, and from which the two exhaust-channels P open, carrying the exhaust-steam 50 down into the hollow base, and from thence

out through the exhaust-pipe Q. The two steam-channels form steam-ports R R in the inner side of each of the valve-chamber, one above and one below the exhaust-port S, while 55 the live-steam channel forms a port, T, in the top of the chamber, in which an oscillating valve, U, rocks. This valve is Y-shaped in section, forming two wings, V, radiating from the shaft W, upon which it is fastened, and 60 extending out to the inner surface of the valve-chamber, and a shorter wing, X, having a longitudinal rectangular groove, Y, in which the square central portion of the valve-shaft W fits. By this construction of the shaft and the 65 valve it will be seen that the latter may be slid in from the end of the valve-chamber upon the shaft without requiring any further fastening, and the recess Z between the two wings is large enough to span one of the steam-ports and the 70 exhaust-port at the time connecting them, while the other steam-port and the live-steam port are connected, the steam passing around the back of the valve. The valve-shafts are provided at one end with cranks a, connected by a rod, b, 75 hinged to their wrist-pins, and are adjusted in such a manner that as they are operated simultaneously by suitable connection to an eccentric upon the drive-shaft, they will alternately admit steam upon the opposite sides of 80 the wings of the piston, exhausting upon the other side, thus causing the piston to be oscillated and operating the engine.

To insure a perfectly steam-tight packing of the cylindrical portion of the piston the inside of the cylinder is longitudinally recessed or grooved at c, on each side of the sector-shaped recesses, and packing-strips d are inserted in these grooves, bearing against the surface of the cylindrical piston, while the 90 ends of the piston are packed by means of packing-rings e, inserted in annular grooves f in the heads of the cylinder, and forced against the ends of the piston by means of spiral springs g, secured in the heads of the cylinder 95 by means of caps h, and bearing against the outside of the packing-rings.

The wings C have recesses or grooves i in their tops and ends, and a number (three or more or less) of L-shaped strips, j, are placed 100 in these grooves, the horizontal parts of which strips are of unequal length, but placed in

such a manner that the ends of the longer ones inserted from one side meet the ends of the shorter strips inserted from the other side, as shown in the drawings, in such a manner that no two joints fall in the same transverse line. These strips are pressed out against the sides and heads of the sector-shaped recesses by means of elliptic springs *k*, bearing against the bottoms of the recesses *i* and against the inner edges of the packing-strips, and by means of spiral springs *l*, bearing against the vertical ends of the recesses and against the inner edges of the vertical ends of the L-shaped strips.

15 The piston-shaft is journaled in four bearings, *t*, one in each head of the cylinder and one on each side of the crank.

To insure a perfect concentricity of the several bearings, I prefer to construct them in the following manner, viz: *m* is the outer casing of the bearing, which is bored out conically with an annular recess or groove, *n*, into which the oil-cup opens. *o o* are the boxes, made of any desired box metal, having inner concave cylindrical bearing-surfaces and outer conical surfaces fitting into the conical bore of the bearing.

The outer thicker ends of these boxes have annular grooves *p* near the ends, forming annular flanges *q*, which fit into an annular groove, *r*, in the inside of a screw-threaded cylindrical cap, *s*, which fits into the outer screw-threaded end of the casing *m*, and serves, when the boxes become worn by use, to take up the wear, by screwing it farther in, pressing the boxes farther in, when they, by their cone shape, will be brought to bear tightly upon the shaft and keep the bearings truly centered. The top of this cap is closed in the two end bearings, while in the bearings for the inner portion of the shaft the cap is open to admit of the shaft passing through the same. By having the annular groove or recess *n* encircling the boxes the latter may always be kept surrounded with oil, keeping it cool, while sufficient oil for lubri-

cating the shaft is admitted between the edges of the boxes.

A pump, *u*, of a construction similar to the engine, with the exception of the valves, may be placed above the engine and connected to the same by means of a connecting-rod, *v*, hinged to a crank, *w*, upon the piston-shaft of the engine, and to a crank, *x*, upon the piston-shaft of the pump, rocking the pump-piston simultaneously with the engine-piston.

55 The operation of the engine will be readily understood by the foregoing description, taken in connection with the accompanying drawings, without further explanation.

Having thus described my invention, I claim and desire to secure by Letters Patent of the United States—

1. The combination, in a steam-engine of the described class, of the cylinder having sector-shaped recesses, live-steam channel *L*, steam-channels *N N* and *O O*, and exhaust-channels *P P*, and the winged oscillating piston, with the cylindrical valve-chambers *M*, having live-steam ports *T*, steam-ports *R*, and exhaust-ports *S*, the valves *U*, having radial wings *V*, and longitudinal rectangular recesses *Y* in their shanks, the square valve-operating shafts *W*, rocking in axial bearings in the valve-chambers, and the means for rocking the same, as and for the purpose shown and set forth.

65 2. The combination, in a steam-engine of the described class, of the wings *C* upon the piston, having grooves *i* in their tops and sides, and provided with the elliptic springs *k* and spiral springs *l*, with the L-shaped packing-strips *j*, placed with their inner ends overlapping each other, as described, as and for the purpose shown and set forth.

75 In testimony that I claim the foregoing as my own I have hereunto affixed my signature in presence of two witnesses.

WILLIAM TELL BAKER.

Witnesses:

HENRY T. NICCUM,
L. M. MARVIN.
